HAT CONSTRUCTION

Filed Feb. 7, 1931

UNITED STATES PATENT OFFICE

EDWARD P. CUNNINGHAM, JR., OF NEW ROCHELLE, AND ALPHONSE E. RIOUX, OF ROCKVILLE CENTER, NEW YORK, ASSIGNEES TO EDWARD P. CUNNINGHAM, INC., OF NEW YORK, N. Y., A CORPORATION OF NEW YORK

HAT CONSTRUCTION

Application filed February 7, 1931. Serial No. 514,278.

This invention relates to hat construction and it comprises a hat having a body composed of straw, felt or other permeable material, an outer ornamental band, an inner sweat band and stitches or threads holding the outer and inner bands in place, the stitches, or some of them, being waterproofed against passage of perspiration therein; it further comprises processes wherein a waterproofing agent is applied to the stitches after the hat has been partly or wholly assembled, as will be more fully hereinafter described.

Our invention is primarily concerned with preventing the staining and discoloration of the ornamental textile bands of straw and felt hats due to perspiration. After a short period of use especially on warm days, these bands, usually made of silk or other expensive fabric, are invariably soiled as a result of perspiration passing from the forehead of the wearer through the body of the hat and saturating the outer ornamental band. The problem of preventing this undesirable phenomenon has been a long standing one. Many solutions have been proposed and these have generally consisted in disposing some sort of waterproof liner or strip between the sweat band and the body of the hat. Although a large number of patents have been granted for expedients of this kind, the problem still persists. Of late, it has been considered that most, if not all, of the perspiration works its way through the holes in the leather sweat band through which the stitches or threads holding the sweat band to the hat also pass. Accordingly, it has recently been suggested to coat the inner surface of the sweat band, that is, the rough surface adjacent the body of the hat, with a film or coating of rubber on that portion of the sweat band through which the stitches pass. This expedient has been founded upon the theory that the film of rubber about the hole or perforation in the sweat band will tend to contract about the stitch or thread passing therethrough, preventing egress of the perspiration in this manner.

The sweat band in a hat performs a two-fold function. It provides a soft cushion against the forehead and holds the hat in

place. Moreover the sweat band is absorbent to a certain degree so that it will pick up a moderate amount of perspiration. At least a portion of the perspiration, however, ordinarily evaporates from both surfaces of the sweat band and it is therefore necessary that the inner surface of the sweat band adjacent the body of the hat be substantially free of a film of rubber which would prevent such normal evaporation if the full usefulness of the sweat band is to be realized.

We have now determined that, in contrast with commonly held beliefs, most of the perspiration soiling the ornamental band flows by capillary action through the threads or stitches holding the sweat band and ornamental band to the hat, thus passes into and through the felt or straw body and finally to the outside of the hat where it then discolors the ornamental band. This discovery probably accounts for the failure of liners, waterproof strips, and the like to prevent soiling because little, if any, perspiration actually passes from the leather of the sweat band to the body of the hat by mere mechanical contact of the sweat band with the hat. Most of the perspiration which actually passes through the sweat band will evaporate from the surface thereof next to the hat.

We have now found that hats of this type can be completely protected against perspiration stains provided the thread or stitches joining the ornamental band to the body of the hat are waterproofed with a suitable waterproofing agent. Moreover, in our invention, we also waterproof the stitches holding the sweat band to the hat and seal the seam defining the lower meeting edge of the sweat band with the hat body. By these three expedients, chiefly either or both the first and second one, we effectively seal all those portions of the hat through which perspiration can flow and thus prevent the passage of the perspiration from the head of the wearer to the outside of the body of the hat and to the ornamental band encircling it.

Waterproofing the threads holding the ornamental band in place prevents any perspiration which has worked through the

holes and stitches in the sweat band from flowing through the hat body and this alone markedly protects a hat from perspiration stains. Waterproofing the stitches of the sweat band, or using a waterproof thread for stitching the band in place prevents the perspiration from reaching the ornamental band stitches so that these two expedients block those portions of the hat which we have found constitute the primary outlets for the perspiration soiling the ornamental band.

In the appended single sheet of drawings we have illustrated our invention in detail.

15 In the drawings,

Figure 1 is a cross section of a conventional hat,

Fig. 2 is an enlarged cross section showing the position of the stitches in greater 20 detail,

Fig. 3 is also a cross sectional view of a portion of the hat showing the point of application of the waterproofing agent,

Fig. 4 is a view of a section of the hat 25 body showing the position of the threads which hold the ornamental band to the outside of the body, and

Fig. 5 illustrates one method of applying the waterproofing agent to the hat after it 30 has been fabricated.

In the drawings like reference characters refer to like elements.

Referring more particularly to Fig. 1, 1 35 is a conventional hat body which may be composed of felt, straw or other typical hat material. The hat body is provided with an ornamental band 2 on the outside thereof and an inner sweat band 3. The sweat band is held to the hat by stitches 4, more clearly 40 shown in Figures 2, 3 and 5 and the ornamental outer band is held by stitches 5.

Stitches 4 are generally applied by a machine stitching operation, Fig. 5 indicating the row of stitches collectively at 8. These 45 stitches do not ordinarily pass all the way through the body of the hat. They take the position shown in the drawings. The outer band is stitched by hand or machine and the 50 stitches are rather far apart as shown at 5 in Fig. 4, the showing in Fig. 4 being the inner surface of the hat body with the stitches passing therethrough. Stitches 5 pass completely through the body of the hat and extend 55 along the interior thereof between the sweat band and the hat as shown in Fig. 4.

Fig. 3 illustrates the point of application of our waterproofing material to the threads. The waterproofing agent is applied to that 60 portion of the threads as at 9 lying between the sweat band 3 and the body of the hat 1. We do not ordinarily apply the waterproofing agent to the stitches on the outside of the sweat band shown at 10 in Figs. 2 and 3. 65 Upon application of the waterproofing agent,

the stitches or threads become saturated therewith so that they are no longer permeable to moisture or perspiration.

The waterproofing agent flows along and into the threads so as to saturate them for some distance into the felt body of the hat. The flow of perspiration is effectively blocked in the stitches themselves and thus no perspiration can pass through them to and through the body of the hat and to the exterior band.

In Fig. 5 we have illustrated one convenient way of practicing our invention. After the hat has been assembled in the usual manner, we bend down the sweat band 3, or even turn it inside out so that access to the row of stitches is had. The waterproofing compound can then easily be applied by an ordinary brush to the row of stitches at point 9. During this waterproofing process the stitches 5 which hold the ornamental band to the body of the hat are also impregnated with waterproofing agent and if this has not been done to the required degree we deliberately coat that portion of the hat body along the line of stitches 5 as shown by the shading 11.

In our invention, we avoid coating the sweat band with the waterproofing agent insofar as possible and do not rely upon any waterproofing of the sweat band itself. During the waterproofing of the threads 4 at point 9 thereof some of the waterproofing agent may accidentally coat the sweat band but such is regarded as an unavoidable loss of waterproofing agent and unnecessary to the success of our invention.

In fact, coating of the sweat band is also detrimental because it decreases the area of the sweat band available for the normal evaporation of perspiration as previously explained.

When using silk sweat bands in light-weight hats, we take care that none of the waterproofing agent coats the silk band and rely chiefly upon waterproofing the stitches 5 which hold the ornamental outer band in place.

During the waterproofing operation, some of the waterproofing material tends to flow in between the sweat band 3 and the body of the hat 1 beneath the threads 4 so that a waterproof seal is established between the lower edge of the sweat band and the hat as illustrated at 6 in Figures 3 and 5. While this is not essential, such sealing of the seam 6 prevents any moisture from flowing down along the outer portion of the sweat band and up between the sweat band and the body of the hat.

In the practice of our invention, the holes in the sweat band through which the stitches or threads pass are sealed or filled but we do not rely upon any contraction of a rubber film about the threads. The amount of water-

proofing agent accidentally coating the sweat band itself is minute and insufficient to form any sort of contracting rubber film about the threads. Furthermore, our waterproofing agent is applied to the threads holding the sweat band after the hat has been fabricated so that the only effect of the waterproofing material on the sweat band itself is to seal the holes through which the stitches pass.

10 In a modification of our invention, we waterproof the stitches 5 which hold the ornamental band in place and waterproof the area 11 shown in Figure 4 prior to stitching in the sweat band. After stitches 5 have 15 been waterproofed, the sweat band is then sewed in the hat and the waterproofing agent applied to stitches 4 as described.

When applying the waterproofing agent to the body of the hat along the line of stitches 20 5 before the sweat band has been stitched in place, we find it advantageous to coat the body of the hat at the junction of the crown with the brim beneath the row of stitches 5 so that when the sweat band is stitched in 25 the hat the lower end of the sweat band is in contact with a waterproofed area 12. When the waterproofing agent is applied to the area 12, both the stitches passing through the sweat band and those encircling its lower 30 edge are forced to pass through the section of hat body so waterproofed.

Instead of waterproofing stitches 4, we can use a waterproof thread, such as a thread saturated or impregnated with a rubber 35 compound or with paraffine or other waterproofing agent and simply stitch the sweat band in place by means of such a thread. This works very well provided the stitches 5 holding the ornamental band in position have been water- 40 proofed as described.

Generally, we apply the waterproofing material to the thread about the whole circumference of the hat 1. We can decrease the expense of applying the waterproofing agent 45 by simply waterproofing the threads in the forehead portion of the hat. It is well recognized that most of the soiling and discoloration of the ornamental band occurs in the front of the hat where the sweat band contacts with the forehead of the user. However, very often a felt or straw hat will develop a ring of discoloration encircling the brim of the hat for a distance of as much as an inch outwardly from the crown. This is 50 especially noticeable in light colored felt and straw hats and is possibly due to dirt adhering to the brim because it has become wet to some extent with perspiration. Our invention completely prohibits this if saturation 55 of the threads around the whole circumference of the hat is practiced.

In the practice of our invention, a number of different waterproofing agents are available. Among the best of these are various 60 freely flowing rubber cements. A latex ce-

ment, or other water base cement is especially advantageous because such cements or waterproofing agents rapidly saturate the threads. The latex may be of the type to which sulfur has been added. It may be a so-called artificial latex which consists of an aqueous dispersion of rubber in water. There are a number of such rubber preparations on the market and we do not wish to be restricted in regard to any particular cement. The cement chosen should be free flowing and one which easily penetrates the threads so that the threads become fully saturated with the agent.

70 Paraffine wax emulsions, aqueous casein waterproofing agents, and numerous other compositions commonly used for waterproofing purposes, can also be used but for all practical purposes, a latex preparation is 75 most suitable and convenient.

80 We are aware that it has been suggested in the prior art to apply one or more linings between the sweat band and the body of the hat and to coat, but not saturate, certain of the stitches holding such linings to the body 85 of the hat with shellac. We do not therefore claim this method of construction. Our invention is primarily directed to the protection of an ordinary hat, assembled in the ordinary way with the ordinary elements, and not a hat fabricated with one or more liners between the sweat band and body of the hat, the sweat band itself being stitched to the liners and not the hat body. Our invention dispenses with such liners or attachment 90 strips and we waterproof the actual stitches which unite either or both the sweat band and ornamental band directly to the body of the hat.

95 In view of the foregoing it will be apparent 100 that our invention blocks or seals all portions of the assembled hat through which perspiration can gain access to the ornamental band and to the brim of the hat.

105 Our method of protecting a hat against 110 soiling due to perspiration has a number of advantages. Among them are the absence of any water-proof strips or liners disposed between the sweat band and the body of the hat. When such are employed they increase 115 the weight of the hat and decrease the inner size of the hat so that one normally wearing a hat of a certain size would be obliged to wear a hat having an oversize body which would not look well upon the wearer. Such liners are also uncomfortable. Moreover, 120 the practice of our invention does not involve the use of specially treated sweat bands since the hat is fabricated in the ordinary way and, by a simple operation upon the hat after it has been made, flow of perspiration to the exterior band and soiling thereby is effectively prevented.

125 It will be apparent that our method is also adaptable to hats which have been used for some time and can be applied by 130

the renovator when the hat is being cleaned and reblocked. If desired an ornamental band which has become soiled due to perspiration can be replaced by a clean band and at 5 the same time the clean band can be completely protected against soiling and discoloration by the application of a waterproofing agent in the manner which we have described.

What is claimed is:

- 10 1. A hat comprising a hat body, an ornamental band affixed to the body by stitches, and a sweat band fixed to the body by stitches, so that the sweat band is in direct contact with the body of the hat itself, the stitches 15 joining the ornamental band and the sweat band to the hat body being saturated with a waterproofing agent to render them impermeable to the passage of perspiration at least in the portion of said stitches lying between the sweat band and the body of the hat.
- 20 2. A hat including a hat body and a sweat band directly stitched thereto, so that the sweat band is in direct contact with the body of the hat itself, the threads constituting 25 the stitches being saturated with a waterproofing agent to render them impermeable to perspiration in the portion thereof lying between the band and the body.
- 30 3. A hat including a hat body and a sweat band directly stitched thereto so that the sweat band is in direct contact with the body of the hat itself, the threads constituting 35 said stitches being saturated with rubber in the portion thereof lying between the band and the body whereby the threads are rendered impermeable to perspiration.
- 40 4. A hat including a hat body and an ornamental band stitched thereto, the threads constituting said stitches being saturated 45 with a waterproofing agent to render them impermeable to perspiration at least in those portions thereof which lie along the inner surface of the hat body.
- 50 5. A hat including a hat body and an ornamental band affixed thereto by stitches the inner surface of the hat being impregnated with a waterproofing agent along the line of 55 stitches holding the band in place.
- 60 6. The process of protecting the outer ornamental band of a hat having an inner sweat band directly stitched to the hat so that the hat body and sweat band are in direct contact with each other, against discoloration due to 65 perspiration which comprises applying a liquid waterproofing agent to the threads holding the sweat band to the hat at a point between the sweat band and the hat after the sweat band has been stitched in place whereby the threads themselves become saturated 70 with the waterproofing agent at least in those portions of the threads which lying between the inner surface of the hat body and the surface of the sweat band which is in contact with the hat body.
- 75 7. The process which comprises coating the

interior of a hat body with a waterproofing agent along the longitudinal area roughly defined by the line of stitches which hold the ornamental band in place, then sewing the sweat band in the hat and then waterproofing 70 the stitches holding the sweat band by the application thereto of a waterproofing agent between the sweat band and the hat body.

In testimony whereof, we affix our signatures.

EDWARD P. CUNNINGHAM, Jr.
ALPHONSE E. RIOUX.
